COMBINED TOY TRUCK AND WOOD CHIPPER

Elaine Ouellet, 3 Oakmont Ave.,
Westminster, Mass. 01473

Filed Aug. 4, 1972, Ser. No. 277,894

Term of patent 14 years

Int. Cl. D21—01

U.S. Cl. D34—15 AJ

FIG. 3

FIG. 4

FIG. 1 is a left side elevational view of a combined toy truck and wood chipper showing my new design, the right side being a mirror image thereof;

FIG. 2 is a top plan view thereof;

FIG. 3 is a rear elevational view thereof; and

FIG. 4 is a front elevational view thereof.

I claim:

The ornamental design for a combined toy truck and wood chipper, as shown and described.
